UNITED STATES PATENT OFFICE.

VICTOR BARRETO, OF MARLOW, ENGLAND.

ELECTRICAL IGNITION FOR INTERNAL-COMBUSTION ENGINES.

932,239.

Specification of Letters Patent. Patented Aug. 24, 1909.

Application filed May 11, 1908. Serial No. 432,054.

To all whom it may concern:

Be it known that I, Baron VICTOR BARRETO, a subject of the King of Great Britain, residing at Quarry Court, Marlow, in the county of Buckinghamshire, in England, have invented new and useful Improvements in Electrical Ignition for Internal-Combustion Engines, of which the following is a specification.

10 This invention relates to high tension distributors designed for use in connection with a magneto-electrical machine, so as to provide a high tension spark for the purpose of firing a charge in petrol motors or other internal combustion engines, the object being to produce a correctly timed high tension firing spark, without the aid of a low tension contact breaker. The current may be derived from a low tension magneto-machine 15 in combination with a suitable transformer or from accumulators connected through a trembler with the primary winding of a suitable induction coil, without the use of a low tension contact breaker in such a manner, that the secondary or high tension winding is under continuous sparking conditions and the high tension current produced is connected directly with my novel distributor, as hereinafter described. If a 20 high tension magneto-machine or high frequency machine is used, the transformer may be dispensed with, and the high tension current produced by this machine or from an alternating current machine may be connected directly to the distributor in the same 25 manner.

It has been found difficult to correctly time high tension ignition current with a distributor, unless a low tension contact breaker is employed, owing to the uncertainty of the timing, due to the liability of the high tension spark to cause ignition, before the corresponding sparking poles or points arrive opposite each other, when the 30 movable distributing arm is caused to revolve in the usual manner, because the high tension current tends to form an arc before the revolving arm arrives at its proper position. To overcome this difficulty, I employ a distributor so arranged, that the high tension current is more or less continuously earthed or short-circuited, until the movable pole or arm has arrived within a short distance from the stationary timing point, firing point or pole, which is mounted in the distributing box, but insulated from the

earthened section of the same by means of porcelain or other suitable non-conducting material, and which is preferably surrounded in addition by an air space or gap.

In the accompanying drawing Figure 1 is a sectional face view of a distributor embodying my invention. Fig. 2 is an axial section. Fig. 3, is the lever. Figs. 4 and 5 represent a modification.

a indicates a metallic cylindrical casing provided with four vulcanite rings *b* and washers *b'* each of which contains a metal plate *c* forming the pole of a terminal *d*, *e* represents a disk of insulating vulcanite, 60 mounted on a steel sleeve *m* and carrying a metallic sparking gap arm *f*. The disk *g* of the latter makes contact with a spring contact piece *i* inclosed in a tube *i'* extending through the vulcanite cover of 70 the distributor and connected with the terminal *j* supplied with current from the high tension coil of the transformer or from the magneto machine (not shown). The said terminal *j* is formed on a cap *j'* mounted on the said tube *i* by a bayonet joint.

The cylindrical casing of the distributor is connected with the metallic framework and therefore to ground through the terminal *h* and a wire (not shown).

The steel sleeve *m* is mounted on a shaft, (not shown) set in motion from the crank-shaft or cam-shaft of the engine and is supported in a boss or axle bearing *a'* formed in the casing of the distributor.

If the shaft carrying the sleeve or hollow axle *m* of the sparking gap arm *f* is caused to revolve, the high tension current entering from the transformer or magneto-machine through the terminal *j* spring *i* contact piece *i* and extremity *g* of arm *f* will spark across the air space which has preferably a width of about $\frac{1}{16}$ inch to the casing *a*, the sparks forming a continuous stream, until the sparking gap arm *f* arrives opposite one of the poles *c*; the short circuiting then ceases, owing to the insulating material at *b*. As soon as the arm *f* faces one of the terminals *c*, the radial distance from which is preferably about $\frac{3}{32}$ inch, the high tension current passes in the usual manner to the sparking plug connected with the same and causes ignition. When *f* has passed beyond *c*, a short circuit is formed and sparks are again formed from the arm *f* to the cylindrical wall of the casing *a* until the sparking arc reaches the next pole *c* so as

to supply current to the second sparking plug and so on alternately.

Fig. 3 shows a lever n , which may be mounted on the boss a' and fixed at the desired angle by means of a clamping screw.

h represents the ground terminal connected by a wire with the metallic framework.

Figs. 4 and 5 are detail views of a modified pole-piece or sparking block c' , surrounded by an air gap p , which the revolving sparking arm must traverse before it faces the pole. Fig. 4 is a section corresponding to Fig. 1, and Fig. 5 a section corresponding to Fig. 2.

15 The terminal screw fixed to the pole-piece passes through a vulcanite cover or plate q fixed to the distributor casing by screws r .

Instead of having four poles or terminals c , as shown in the drawing, which would be 20 suitable for a four-cylinder engine, any other desired number of them may be distributed along the circumference of the casing, one for each cylinder of the engine, the same revolving arm f thus serving to operate 25 one or more igniting circuits one after another and a metallic path being formed for earthing each circuit.

Other modifications of my distributor may of course be devised, all of which embody

the feature, that during the time the movable contact piece or pole is not opposite one of the fixed contact pieces or poles, a suitable by-path is offered to the current from the movable pole.

What I do claim as my invention, and desire to secure by Letters Patent, is—

In electric igniting devices for internal combustion engines, a rotary high-tension distributor comprising a box or casing of conducting material having in its circumference one or more stationary pole pieces or terminals insulated from the box, each forming the pole of an igniting circuit, a movable 40 sparking gap arm connected with a high tension circuit and adapted to turn on the axis of the box, so as to face the stationary pole or poles and thereby to lead high tension current to the same once at every revolution, and a grounding device connected with the said box, substantially as described 45 and for the purpose specified.

In testimony whereof I affix my signature in presence of two witnesses.

VICTOR BARRETO.
